CLOSURE MEANS FOR CAR COUPLERS

William J. Metzger, East Cleveland, Ohio, assignor to National Malleable and Steel Castings Company, Cleveland, Ohio, a corporation of Ohio

Application October 22, 1947, Serial No. 781,279

1 Claim. (Cl. 220—24)

1 This invention relates to closure means for closing top openings in car couplers.

Car couplers are commonly made to allow for either top operation or bottom operation, whichever is preferred. If a coupler is fitted for bottom operation, it becomes necessary to provide means for closing the hole provided in the top of the coupler head for top operation in order to prevent entry into the coupler head of foreign materials which would prevent proper operation of the coupler.

In the past the various forms of caps which have been used to close top lock lifter openings in car couplers have in general been unsatisfactory. Such caps were usually driven into place and frequently became loose in service and were lost, leaving the coupler open to the entry of foreign matter. In many cases it was impossible to tighten the caps properly in the holes when they were initially applied due to variations in hole and cap dimensions. Accordingly, it is the main object of my invention to provide a novel closure cap which is simple and economical to make and which is securely fastened to the coupler head by means of welding.

Other objects and advantages of my invention will be apparent from the following description of my invention taken in conjunction with the drawings in which:

Fig. 1 is a vertical view of a coupler head showing a cap embodying my invention applied to the coupler, the section through the cap, being taken along line A—A of Fig. 4.

Fig. 2 is a sectional view of the cap taken along line A—A of Fig. 4.

Figs. 3, 4, and 5 represent side elevational, bottom plan, and end views respectively of the cap.

Referring to the drawings there is shown the top portion 10 of a car coupler head having the usual top lock lifter hole 11 found in most couplers now in service. The side walls of hole 11 converge upwardly. The cap for closing hole 11 comprises a cover plate 13 which is formed with three integral downwardly and outwardly extending lugs 14. Cover 13 is somewhat larger than the hole so as to overlap the opening and present a substantial surface of engagement between the cap and the top surface of the coupler. The shape of the cap as viewed in plan is similar to that of the hole, three sides of the cap being straight and the other rounded. Since lugs 14 are formed from plate 13 by cutting and depressing portions thereof, openings 15 are thereby made in plate 13 adjacent the lugs for receiving

2 a weld for securing the cap to the coupler head. It will be observed that lugs 14 are preferably formed so that a substantial portion of plate 13 exists outwardly of opening 15, as at 16, and when the cap is welded to the coupler head, the weld remains inwardly of the edge of the cap and thus allows a smooth edge thereon.

Lugs 14 are preferably located as shown in Fig. 4 with two of them facing the rounded side 10 of the cap and the other facing the opposite straight side. The lugs are so formed that their ends engage the sides of hole 11 when the cap is applied and thereby serve to position the cap as well as prevent any weld material from dropping into the coupler head as the cap is being welded thereto. It will be observed that openings 15 in the cap are sufficiently large to permit a substantial weld between the cap and coupler head. Lugs 14 in addition to the aforementioned functions also provide in conjunction with the adjacent weld a truss effect which reinforces and strengthens the cap against bending or impact stresses accidentally applied thereto in service.

It will be understood that the lugs may be located on the cap in any manner desired. For example one may be positioned facing the curved side and two positioned facing the opposite straight side.

The cap is preferably formed from sheet or 30 plate steel of suitable gauge and may be economically made by a blanking operation to shape the body 13 and a cutting and forming operation for making the lugs 14.

The terms and expressions which I have employed are used as terms of description and not of limitation, and I have no intention, in the use of such terms and expressions, of excluding any equivalents of the features shown and described or portions thereof, but recognize that 40 various modifications are possible within the scope of the invention claimed.

What I claim is:

In combination with a car coupler having a top lock lifter opening, a cap closing said opening and secured to said coupler, said cap comprising a plate having a plurality of integral lugs inwardly of the edges of said plate extending downwardly and outwardly toward the walls of said opening, the ends of said lugs serving to position said plate with respect to the walls of said opening, said plate having an opening positioned outwardly of each lug and inwardly of the edge of the plate, the inner edge of each opening extending along the end of the lug, and weld material positioned in each of said plate openings and

substantially filling the openings and securing said lugs to the walls of said coupler opening, said lugs in conjunction with said weld material forming a truss effect for strengthening said plate against bending or impact stresses applied thereto.

WILLIAM J. METZGER.
